UNITED STATES PATENT OFFICE.

GEORGE RALPH BAKER AND WILLIAM EDWARD PRESCOTT, OF LONDON, AND CHARLES WILFRED GILDERDALE, OF NEW EARSWICK, ENGLAND, ASSIGNORS TO ROWNTREE AND COMPANY LIMITED, OF YORK, ENGLAND.

METHOD AND APPARATUS FOR GRADING SOLID MATERIALS.

Application filed January 31, 1924, Serial No. 689,737, and in Great Britain February 26, 1923.

This invention relates to methods and apparatus for grading solid materials.

In the art to which the present invention relates it is a fact that as the size of particles of a powdered substance is decreased said particles become more and more easily influenced by air currents, and when an extremely fine powder is produced it may readily be carried in a gentle current of air, 10 even when the material has a high specific gravity.

In other words the smaller the particles of a powdered substance, the more important becomes the influence of the surface friction 15 of a current of air thereon in relation to the force of gravity. This fact is made use of in the separators generally used for grading fine powders, in which powder-laden air is blown into a settling chamber, the coarsest 20 grade being deposited most quickly and falling near the air inlet, the finest powder on the other hand being deposited at the point farthest from the air inlet. Difficulties arise however where this method is employed for 25 very fine powders in that the air current employed has to be very gentle and eddies due to temperature variation or other causes quickly interfere with the correct working of the settling chamber, furthermore such 30 a device has to be very large to obtain any reasonable output of material.

The object of the present invention is to provide a novel and more accurate and positive method than at present in use for grading particles of solid material by means of a current of air.

According to the present embodiment of our invention shown in the drawings, currents of air in which the material to be graded is distributed are caused to pass inwards through a revolving separator whereby the material and air are caused to rotate with the rotor of the separator and to be subjected to the action of centrifugal force, the regulation being such that the air current overbalances the centrifugal force as regards the smaller or light particles and the centrifugal force overbalances the air current as regards the larger or heavy particles, 40 so that the latter are projected outwards against the air current whereas the smaller or light particles are carried by the air current. 45

In the operation of such a method the particles of solid material in the air will be 55 acted upon by three forces, viz:—

Firstly, the skin friction of the air current which has carried them into the zone of action of the rotating member and exerts a 60 force on the particles tending to carry them with the air current towards the centre of said member.

Secondly, the force of gravity, and

Thirdly, the centrifugal force acting on 65 the particles as they are carried round by the rotating member.

If the speed of the rotating member or rotor is at all high, the force of gravity becomes extremely small in relation to the 70 centrifugal force so that there are substantially but two opposing forces acting on the particles, viz, that of centrifugal force tending to carry the particles outward from the centre and the skin friction of the air current moving towards the centre of the rotor. 75 The smaller the particles the stronger will be the influence of the air current when the rotor is running at a constant speed and it will be apparent that with a given rotor speed and speed of air current all particles 80 larger than a certain size will be rejected or driven off centrifugally, whilst all smaller particles will be carried by the air current towards the centre of the rotor. If the rotor speed is increased, still finer particles will be 85 rejected and only those particles of such size that the skin friction of the air current overcomes the centrifugal force due to the speed of the rotor will be carried in the air current towards the centre.

As the centrifugal force due to the speed 90 of the rotor and the strength of the air current passing through the lines of centrifugal force may be varied within extremely wide limits, it will be seen that a very exact and 95 readily controlled means of grading granulated or powdered substances is provided by which it has been found possible to grade very fine powders far more accurately and efficiently than by any means hitherto 100 known.

Furthermore a great saving in the size 105 of apparatus is effected, due to the fact that relatively large forces are employed compared with gravity. In any ordinary expansion separator an air current is used against

gravity and for very fine powders only very gentle air currents can be employed, and this necessitates a very bulky apparatus.

In this invention high air velocities can be used to balance high centrifugal force, so that the same amount of fine material can be carried over in a very much smaller apparatus.

A further advantage is that by balancing the two large forces as stated eddy currents have little or no effect on the efficiency of separation, whereas in an ordinary expansion chamber they seriously interfere with the accuracy of grading of very fine powders.

The invention may also be employed for separating two powdered materials of different specific gravities and in this case the particles to be separated need not necessarily be of different sizes.

An embodiment of apparatus for carrying out the present invention is illustrated in the accompanying drawings in which Fig. 1 is a vertical central section, Fig. 2 is a sectional elevation at right angles to Fig. 1, Fig. 3 is a sectional plan on the line A—B of Fig. 1, and Fig. 4 is a partial plan showing the tailings chute hereinafter referred to and with parts removed for clearness of illustration.

The apparatus shown in the drawings comprises an outer stationary casing *a* provided at the top with means, shown as comprising a hopper *a*¹ and worm conveyor *a*², for feeding in the material. This casing is carried by a suitable hollow pillar *a*³ and is open below and shaped to provide a chute *b* for discharge of tailings or heavier particles into which chute leads an inlet *b*¹ for air from any suitable source, such as a cyclone separator, if the material treated is passed thereto after treatment in the present apparatus, as may possibly be done. Located in the casing *a* is the rotor which comprises a central conical drum *c* carrying a number of radial vanes *c*¹ between which are arranged a series of spaced plates or baffles *c*² shown as inclined but which may also be flat, and the drum being provided above with a conical and axial outlet *c*³ extending into the cover *a*⁴ of the casing and connected to a trunk or pipe *d* which leads to a fan, blower or other air exhausting device *d*¹ of any appropriate kind and which, if desired, may have a delivery *d*² to the cyclone separator before mentioned. The vanes *c*¹ preferably extend for the whole length of the rotor between end members formed by the parts *c*³, *c*⁴ and air outlets may be provided on both said end members so that the current of air may be sucked off at both ends, if desired. The fan is shown as driven by pulley *d*³ and belt *d*⁴ from any suitable source of power. The base of the drum *c* terminates in an outwardly flared portion *c*⁴

substantially closing the end of the rotor and the rotor as a whole is carried by a vertical shaft *e*, carried by antifriction bearings *e*¹ and suitably enclosed in a tubular housing *e*² extending through the pillar *a*³ and tailings chute *b* the shaft being provided at its lower end within the bottom of the pillar with a pulley *e*³ driven by belt *e*⁴ from a pulley *f* on a main drive shaft *f*¹, from which also the feed worm *a*² is driven through belt and pulley gear *f*², *f*³.

The outer casing *a* is also provided on its inner surface with radial vanes *g* between which are mounted a number of inclined plates or baffles *g*¹ (which may also be flat similarly to the plates *c*² or of other required shape) the inner edges of which pass between the outer edges of the drum plates *c*² and extend beyond said outer edges for a short distance into the spaces between them. These plates and the outer casing carrying them are made in halves so that they fit together between the plates *c*² of the rotating member. The outer edges of said plates *g*¹ are at varying distances from the wall of the casing *a* to form gradually decreasing passages *g*² from below upwards.

From the above description it will be apparent that the interior of the rotor is subjected to the suctional effect of the fan, tending to draw the air and particles carried thereby towards the centre thereof, and in the operation of the device the material fed into the top of the casing by the worm *a*² is directed by a depending deflector *h*, falls alternately onto the inclined plates *c*² of the rotor and *g*¹ of the casing in succession in a zig-zag course, whilst the rotor is rotated. The air entering at the inlet *b*¹ passes through the channels between the casing plates *g*² and in approaching the rotor carries with it the descending material, it then crosses the region between the rotor plates *c*² where it is subjected to the action of centrifugal force which removes the heavier particles; then carrying with it the lighter particles the air current passes up the face of the conical drum *c* and out at the top through the trunk *d*, for subsequent delivery to the cyclone separator or to be collected in some other way.

The above description discloses in a general way the function of the apparatus but there are other considerations for the efficient working of the apparatus which will now be referred to.

In order to obtain accurate grading it is important that the velocity of the air current passing through the rotor should be approximately equal at all active points of its surface. One way of obtaining this result is by the construction above described in which the rotor is divided into a number of sections by the plates *c*² intersecting the radial vanes *c*¹ and with the axial passages *c*³

c^{10} between the latter ensuring that the air passing through the rotor from the outside inwards crosses the regions between all the plates at substantially the same velocity and travels inwards in directions passing through the axis of the rotor whilst crossing said regions. This result is assisted by the provision of the axial outlet c^2 for the rotor at one end and the conical drum c forming the hub of said rotor, the base of the drum being situated at the closed end of the rotor and the apex of the drum adjacent the air outlet, thus ensuring that the air entering the rotor travels inwards at an approximately uniform velocity in all parts of the rotor. This result is also assisted by the fact that the hub of the rotor is conical, that the spaces between the rotor plates c^2 and the hub increase in an upward direction, and that the spaces between the casing plates and the casing decrease in an upward direction.

It is also important to ensure that all particles passing into the region of the rotor are acted on by centrifugal force of the same intensity, or in other words, that once the particles enter the separation zone of the rotor they are positively carried round therewith, this result being obtained by the provision of the radial vanes c^1 and plates c^2 as above described.

All portions of the material are brought equally under the influence of the air passing into the rotor and the heavier material rejected by the rotor is successively returned to it to ensure that all fine particles are separated therefrom.

Such result is obtained by the relative arrangement of the rotor and casing plates c^2 and g^1 as above described since in operation and more particularly at higher rotor and fan speeds the heavier particles rejected by the rotor take a zig-zag path upwards again between the adjacent edges of said plates and fall back again thereon for further treatment. Also the action of the centrifugal force may force the material over the outer edges of the casing plates g^1 but the current of air outside same will bring it back to be further treated, these operations being repeated until the remaining heavier particles become so densely distributed in the air entering the rotor that they finally pass to the tailings chute b .

An important feature of the action of the present apparatus is that the centrifugal force does not merely drive or flick the material off the rotor plates c^2 as in centrifugal separators of known construction but acts positively thereon at all times against the counter current of air drawn inwards towards the centre of the rotor, and after leaving said plates the centrifugal force practically ceases to act on the material, a

uniform and definitely controlled separation 65 being thus obtained.

The invention also contemplates the employment of a series of apparatus such as described above so that particles of any desired size may be isolated from those of 70 larger or smaller size than those required. It will be apparent that this can be readily accomplished by presenting the fine product passing over with the air through the rotor of one apparatus, to the rotor of a second 75 apparatus running at a higher speed, which will reject the largest of the particles passing the first rotor.

It will be observed that in the apparatus shown in the drawings (which is merely 80 illustrative of one of the various forms in which our invention may be embodied) a continuously-flowing current of air which carries in suspension the material to be separated is maintained, and this current as 85 a whole, with all of its particles held in suspension therein, is positively given a whirling movement. This obviously gives to each suspended particle a certain centrifugal force, the strength of which depends upon 90 the speed at which the current is whirled.

It maintains the particle-bearing current continuously flowing radially of, that is inward toward, the axis of rotation. In fact, the apparatus specifically illustrated maintains a plurality of such currents. Each pair of adjacent vertical vanes c^1 with the bottom cone c^4 and top cone c^3 , between which the vanes extend, forms in substance a duct or passageway which serves to lead 100 the air radially inward toward the axis of the rotor. This duct or passage encloses that portion of the current, and as the rotor revolves it causes this duct or passageway and consequently the entire body of current 105 enclosed by it to be rotated as a whole, and it and all air-borne particles therein are positively rotated at the same angular speed. As a consequence, substantially all parts of the current in such duct have substantially 110 equal velocities and substantially all the air-borne particles therein are subjected to substantially the same intensity of centrifugal force. Undesired eddy currents with the resultant diminished effectiveness of the 115 apparatus are therefore avoided.

The vertical vanes c^1 obviously act in the illustrated embodiment both as the side of such duct or passageway and as a means for causing the current to be given a positive whirling movement.

We are aware that our invention claimed may be embodied or carried out by forms other than that illustrated and described.

What we claim as our invention and desire to secure by Letters Patent of the United States is:

1. The method of grading particles of

4

solid material by the use of a whirling current of air carrying said particles in suspension, which comprises maintaining said current continuously flowing radially inward from without said whirl, and simultaneously positively whirling said current so as to give to the particles in suspension a centrifugal force acting in a direction opposed to said inward flow of said current.

10 2. The method of grading particles of solid material by the use of a whirling current of air carrying said particles in suspension, which comprises maintaining said current continuously flowing radially inward from without said whirl, and simultaneously positively whirling said current so as to give to the particles in suspension a centrifugal force acting in a direction opposed to said inward flow of said current and varying at least one of said steps to vary the size of the product.

15 3. The method of grading particles of solid material by the use of a current of air which is whirled on an axis, comprising maintaining said current continuously flowing inward toward said axis, and simultaneously positively whirling said current bodily on said axis in such manner that substantially all parts thereof move at the same angular speed.

20 4. Apparatus for grading particles of solid material by means of air currents in which the material is distributed, comprising a rotor including a central hub, a plurality of radial vanes mounted on said hub and end members on said hub having an axial air outlet and between which the radial vanes extend for the whole length.

25 5. Apparatus for grading particles of solid material by means of air currents in which the material is distributed, comprising a rotor including a central hub, a plurality of radial vanes mounted on said hub and extending completely between end members on the hub having an axial air outlet, said rotor being divided into a number of sections by plates intersecting said radial vanes and provided with passages in the interior of the rotor connecting all said sections with the air outlet aforesaid.

30 6. Apparatus for grading particles of solid material by means of air currents in which the material is distributed, comprising a rotor having an axial air outlet at one end and closed at the opposite end and including a conical hub the base of which is located at said closed end and the apex adjacent said air outlet, and a plurality of radial vanes mounted on said hub and extending completely between end members carried by the hub.

35 7. Apparatus for grading particles of solid material by means of air currents in which the material is distributed, comprising a rotor having an axial air outlet at one

end and closed at the opposite end and including a conical hub the base of which is located at said closed end and the apex adjacent said air outlet, and a plurality of radial vanes mounted on said hub and extending completely between end members carried by the hub, said rotor being divided into a number of sections by plates intersecting said radial vanes and provided with passages interiorly of the rotor connecting all said sections with the aforesaid air outlet.

40 8. Apparatus for grading particles of solid material by means of air currents in which the material is distributed, comprising a rotor including a central hub, a plurality of radial vanes mounted on said hub and extending completely between end members on said hub and having an axial air outlet and a cylindrical air chamber enclosing the rotor and provided with interiorly directed plates within which the rotor revolves, said plates being so disposed that air entering the rotor approaches the latter in directions passing through its axis.

45 9. Apparatus for grading particles of solid material by means of air currents in which the material is distributed, comprising a rotor including a central hub, a plurality of radial vanes mounted on said hub and extending completely between end members on the hub having an axial air outlet, said rotor being divided into a number of sections by plates intersecting said radial vanes and provided with passages in the interior of the rotor connecting all said sections with the air outlet aforesaid, and a cylindrical air chamber enclosing the rotor and provided with interiorly directed plates within which the rotor revolves, said last mentioned plates being so disposed that air entering the rotor approaches the latter in directions passing through its axis.

50 10. Apparatus for grading particles of solid material by means of air currents in which the material is distributed, comprising a rotor having an axial air outlet at one end and including a central hub, a plurality of radial vanes mounted on said hub and extending completely between end members thereon, a plurality of plates carried by said radial vanes and intersecting same to divide the rotor into a number of sections, said plates being provided with passages connecting all said sections with the air outlet, and a cylindrical air chamber enclosing the rotor and provided with interiorly directed plates within which the rotor revolves, said last mentioned plates being so disposed that air entering the rotor approaches the latter in directions passing through its axis.

55 11. Apparatus for grading particles of solid material by means of air currents in which the material is distributed, comprising a rotor having an axial air outlet at one

- end and including a central hub, a plurality of radial vanes mounted on said hub and extending completely between end members thereon, a plurality of plates carried by said radial vanes and intersecting same to divide the rotor into a number of sections, said plates being provided with passages connecting all said sections with the air outlet, and a cylindrical air chamber enclosing the rotor and provided with interiorly directed plates within which the rotor revolves, said last mentioned plates being so disposed as to leave a progressively smaller air space between their exterior edges and the wall of the air chamber as they approach the air outlet.
12. Apparatus for grading particles of solid material by means of air currents in which the material is distributed, comprising a rotor revolvable about a vertical axis and having an axial air inlet at one end and an axial air outlet at the other, said rotor including a central hub, a plurality of radial vanes mounted on said hub and extending between end members thereon, a plurality of outwardly directed inclined cones on the rotor intersecting the radial vanes, a cylindrical casing surrounding the rotor and a series of stationary funnel shaped cones in the casing located to alternate with the inclined cones on the rotor, the inner diameter of the stationary cones being smaller than the outside diameter of the rotor cones whereby on material being fed by gravity from the top of the apparatus and air entering from below, the material passes through the apparatus in a zig-zag course, falling first on a rotating cone then on a stationary one from which it slides down again onto a rotating cone and so on, being thoroughly separated by the current of air being drawn into the rotor.
13. An apparatus for grading solid ma-
- terial carried by a continuously-flowing current of air comprising a plurality of rotatable vanes arranged to whirl said current positively, and means arranged to cause substantially the entire body of said current to pass radially inward from without the path of travel of said vanes.
14. An apparatus for grading particles of material from a current of air carrying said particles in suspension, comprising a duct enclosing said current and leading the same inwardly toward an axis of rotation, means for bodily rotating said duct and current on said axis, and means for maintaining the flow of said current continuously.
15. An apparatus for grading particles of material from a current of air carrying said particles in suspension, comprising a duct enclosing said current and leading the same inwardly toward an axis of rotation, means for bodily rotating said duct and current on said axis, means for maintaining the flow of said current continuously, and means for varying at least one of said elements to vary the size of the resulting product.
16. An apparatus for grading particles of solid material carried by a whirling air current, comprising conducting means arranged to lead said air radially inward in such manner that substantially all parts of said current shall have substantially equal velocity, and centrifugally-acting means for positively whirling said current in such direction that substantially all air-borne particles therein shall be subjected to substantially the same intensity of centrifugal force.

In witness whereof we have signed this specification.

GEORGE RALPH BAKER.
WILLIAM EDWARD PRESCOTT.
CHARLES WILFRED GILDERDALE.
